UNITED STATES PATENT OFFICE.

JOHN LEVANDER, OF FORESTVILLE, CONNECTICUT.

AERO SWING.

Application filed April 18, 1923. Serial No. 632,830.

To all whom it may concern:

Be it known that I, JOHN LEVANDER, a citizen of the United States, residing at Forestville, in the county of Hartford and

5 State of Connecticut, have invented certain new and useful Improvements in Aero Swings, of which the following is a specification.

My invention relates to improvements in 10 aero swings of the form having a plurality of gondolas or carriages that are individually supported by means of suspension devices so as to swing freely in space, being distributed around a common axis and supported as a group from the upper end portion of a shaft that is provided with means for being rotated so that in use the gondolas or carriages will swing outwardly from the 15 axis as they are carried around, and the object of my invention is to produce an aero swing of relatively diminutive form such as to be adapted to be used as an attraction or novelty in a show-window or the like or as a toy, the details of construction being 20 correspondingly simple and the main parts being adapted to be readily assembled in operative position and taken apart.

In the accompanying drawing:—

Figure 1 is a side elevation of my improved aero swing.

Figure 2 is a plan view of the same.

Figure 3 is a fragmentary view on an enlarged scale of the junction of the shaft of the aero swing proper and the driving 35 shaft of the motor.

Figure 4 shows in detail, views of the connecting piece or hanger of wire and adjacent parts.

My improved aero swing comprises a 40 swing structure 10 that has a central, vertically directed shaft 11 that extends downwardly into a housing structure 12 for a propelling means, such as a spring motor or an electric motor.

45 Said housing structure 12 is a box-like structure that is closed at the upper end of a roof 13 that has an opening 14 for admitting the lower end portion 15 of the shaft 11.

50 The motor may consist substantially of simply a clock of common form that has a shaft 16 that is driven and controlled in the usual manner, said shaft 16 being positively supported by the clock frame. In the present instance, the shafts 11 and 16 are in alignment and the lower end portion 15

of the shaft 11 rests upon and is jointed with the upper end portion 18 of the clock shaft 16, whereby the aero shaft 11 is supported for use.

60 The clock shaft 16 is made of solid material and the aero swing shaft 11 is made of tubing, the latter being of a size so as to be adapted to slip over the projecting end portion 18 of the clock shaft 16. A pin 65 may be used to complete the connection in some cases.

70 The opening 14 in the roof 13 serves as a guide bearing for the lower end portion 15 of the shaft 11.

75 The upper end portion or body portion of the aero shaft 11 is guided by means of a standard 19 that has an opening in the upper end part 20 through which said shaft 11 extends.

80 The standard 19 is made of sheet metal in strip form, is generally of U-shape and positioned inverted, the upper end part 20 thereof being a yoke part that serves to interconnect the two side arms 21.

85 The yoke 20 may be relatively short, as shown, and the side arms generally divergent so that the lower end portions 22 are spread apart suitably to be mounted on the side walls 23 on opposite sides of the motor housing 12.

90 The shaft 11 is capped at the upper end by a ball 24, which latter has an opening that is adapted to receive the tip end portion 25 of said shaft 11, said ball being replaceable by an ornamental figure of any other suitable form.

95 Mounted on the shaft 11 and positioned just below the ball 24 is a top plate 26 that serves as a tension plate and receives the upper ends of the individual suspension devices, of which there are four in the present instance to correspond to the number of gondolas or carriages 27.

100 Said suspension devices are made of chain lengths and comprise in each case an upper member 28 that is relatively short and composed of a single strand, and a lower portion that is composed of two strands 29.

105 At the junction of the upper and lower strands of the chain there may be, as shown, a connecting piece or hanger 30 of wire. Said hanger may be of any proper form for connecting the opposed chain ends and comprises, furthermore an inwardly directed radial arm 32 that serves as the positioning means in cooperation with the opposed end

portion of a radially directed strut 31. Said strut is made of tubing and the arm 32 is inserted in the bore thereof.

The inner ends of the struts 31 are inserted in suitable radial openings 33 in a strut plate 34 that is mounted on the shaft 11, being positioned between the top tension plate 26 and the yoke 20.

The tension plate 26 and the strut plate 34 have each an opening that admits the shaft 11 and each is supported against dropping downwardly by means of a pin 35 that is passed through suitable openings in the shaft.

15 The two chain members 29 of a pair are positioned in slightly spaced relation at their upper ends 45 where they are connected with the hanger 30 and their lower ends are appreciably spread apart and connected to the 20 body portion 37 of the gondola 27, whereby the gondola will be directed substantially at right angles to the radius and will be adapted to move longitudinally or head-on.

25 At one end of the gondola 27 is a lightly constructed two-bladed propeller 38 that is mounted for rotation by means of a pin 39 and at the other end thereof is a rudder 40 of flat plate-like form, and wings 41 are also provided.

30 As shown, the gondola 27 is made to represent an aeroplane and in use the propeller 38 will rotate.

The description given applies to a structure that is nearly two feet high.

35 As details of construction, the tension plate 26 has perforations in the border portion for receiving the upper ends of the short chains 28. Also, the struts 31 abut by their inner ends against the aero shaft 11.

40 The hanger 30 is made of wire and the arm 32 thereof is composed of the two ends of the wire, positioned in spaced relation, and operative as spring members to engage with the opposed wall of the tubing of which the strut 31 is made.

The said hanger 30 is of symmetrical

form. The middle portion 50 thereof is in the form of an upwardly directed loop 50 that receives the end link of the chain that serves as the upper tension member 28 of 50 the suspension device for the gondola. Intermediate said middle portion 50 and the individual arms 51 that compose the double arm 32, on each side, is a pendant loop 52 that receives the opposed upper ends 45 of 55 one of the mating chain members 29 that serve as the support proper for the corresponding gondola.

I claim as my invention:—

1. In an aero swing, a box-like base structure having shaft supporting means, a shaft connected to said means and extending upwardly from said structure, means for guiding the upper end portion of said shaft, an ornamental tip on the top end of said shaft, 65 a tension plate mounted on said shaft adjacent said tip and a thrust plate also mounted thereon and spaced below said tension plate, thrust rods extending outwardly from said thrust plate, hangers at the outer 70 ends of said rods, having each an upwardly directed loop, and having each a pair of pendant hooks, tension chains connecting said loops and said tension plate, and a set of gondola devices hung individually from 75 said hooks.

2. In an aero swing as described in claim 1, said thrust rods being of tubular form, and said hangers having arms for being entered within said rods. 80

3. In an aero swing as described in claim 1, pins inserted through said shaft and below said tension plate and thrust plate serving as the means for positioning said tension plate and thrust plate. 85

4. In an aero swing as described in claim 1, said thrust rods being of tubular form, and said hangers being in the form of a single piece structure with a supporting finger structure for being inserted in the ends 90 of said thrust rods.

JOHN LEVANDER.
